UNITED STATES PATENT OFFICE

CHARLES W. AKERS AND WILLIAM H. FOSTER, OF PRINCETON, WEST VIRGINIA

JOURNAL LUBRICATOR

Application filed October 12, 1928. Serial No. 312,123.

This invention relates to lubrication and its general object is to provide an oiling device for the journals of railway equipment that retains a sufficient film of clean oil about 5 the journal at all times without waste of oil and premature loss of its lubrication qualities.

Another object of the invention is to provide an oiling device to be used in journal boxes and the like that retains oil saturated 10 waste or packing in contacting engagement with the journal under all conditions.

A still further object of the invention is to provide an oiling device for journal boxes and the like that provides for the application 15 of free oil to the box and includes resilient supporting means for packing or waste that is suspended to lie in the oil and engages the journal, with the result the oil is fed to the journal by capillary attraction which insures clean oil, free from grit, dirt and other 20 foreign matter.

A still further object of the invention is to provide an oiling device for journal boxes that requires very little attention other than 25 the replenishing of the supply of oil thereto as the packing or waste will last for an indefinite period of time due to the manner of supporting the same with respect to the journal.

30 Another object of the invention is to provide an oiling device of the character set forth, that is extremely simple in construction, inexpensive to manufacture and efficient in operation and service.

35 This invention also consists in certain other features of construction and in the combination and arrangement of the several parts, to be hereinafter fully described, illustrated in the accompanying drawings and specifically 40 pointed out in the appended claim.

In describing our invention in detail, reference will be had to the accompanying drawings wherein like characters denote like or 45 corresponding parts throughout the several views, and in which:

Figure 1 is a vertical sectional view taken through the journal box and showing the application of our oiling device which forms 50 the subject matter of the present invention.

Figure 2 is a top plan view of the device per se.

Figure 3 is a side elevation thereof.

Figure 4 is a sectional view taken approximately on line 4—4 of Figure 2, looking in 55 the direction of the arrows.

Referring to the drawings in detail, the letter A indicates a journal box of the usual construction and which includes the usual packing or waste containing space B disposed below the journal C. The space B in the present form of the invention is primarily designed for receiving our oiling device as well as to act in the capacity of an oil reservoir as shown in Figure 1 of the drawings. Our 60 oiling device includes a base plate 1 having a relatively large rectangular opening 2 formed centrally therein, and the plate is of a size to fit the bottom of the box as shown.

Formed with and rising from adjacent the 70 corners of the base plate 1 are upright rods 3 having coil springs 4 surrounding the same with the end convolutions engaging the base plate and the waste or packing retainer 5 which is provided with openings to accommodate the upright rods 3 and is held associated therewith through the instrumentality of cotter pins or like fastening elements 6. The coil springs 4 are under compression so as to normally urge the waste or packing 75 retainer to its uppermost position on the rods.

The retainer 5 is substantially channel 80 shape and has a rounded bottom 7, with outwardly opposed directed side walls 8 terminating in parallel flanges 9 which are provided with the openings to accommodate the rods as above set forth. The side walls are formed with arcuate portions above their juncture with the bottom which is provided with a plurality of slots 10 arranged in co-operating pairs for a purpose which will be 85 presently apparent, and the bottom is preferably reinforced by bridging strips 11 which are secured to the under surface of the bottom and portions of the side walls as clearly 90 shown in Figure 3 of the drawings.

The slots 10 of each pair cooperate for receiving a quantity of packing or waste 12, and the packing or waste is of sufficient length to be passed through the cooperating 100

slots of each pair in loop formation with the looped portion disposed in contacting engagement with the journal C while the ends of the packing or waste extend to the bottom of the box so as to be received in oil which may be disposed in the box in any well known manner or through the medium of a system of pipes extending from the bottom or end of the box to a point where oil can be conveniently applied.

From the above description and disclosure of the drawings, it will be obvious that we have provided an oiling device that will supply clean oil to a journal under all conditions and the packing or waste will be disposed in contacting engagement with the journal due to the action of the coil springs in urging the retainer 5 to its uppermost position. The oil will be fed to the journal by capillary attraction, as will be apparent, and the looped portion of the packing or waste is spread to an extent that it will engage a sufficient area of the journal to properly apply the oil thereto, and this spreading is brought about by the engagement of the journal with the packing or waste and the novel shape of the retainer 5 as clearly shown in Figure 1.

It is thought from the foregoing description that the advantages and novel features of our invention will be readily apparent.

We desire it to be understood that we may make changes in the construction and in the combination and arrangement of the several parts, provided that such changes fall within the scope of the appended claim.

What we claim is:

The combination with a journal box and a journal mounted therein, of a base plate disposed within the bottom of the box and having a central opening therein, rods rising from the plate adjacent the corners thereof, a packing retainer comprising an elongated body of substantially U-shaped formation in cross section having its opposed side walls extended upwardly and outwardly in spaced concentric relation to the journal, and terminating to provide horizontal flanges having openings to receive said rods, yieldable means for supporting the retainer on the rods, the bottom of said retainer having longitudinal slots at opposite sides of the longitudinal center thereof, and reinforcing strips bridging the bottom of the retainer and extending across said slots.

In testimony whereof we affix our signatures.

CHARLES W. AKERS.
WILLIAM H. FOSTER.
